UNITED STATES PATENT OFFICE.

MAX FREITAG, OF ALFELD, GERMANY.

MACHINE FOR PUNCHING AND SETTING FASTENERS IN PAPER.

1,239,382.

Specification of Letters Patent.

Patented Sept. 4, 1917.

Application filed April 22, 1913, Serial No. 768,691. Renewed September 19, 1916. Serial No. 121,086.

To all whom it may concern:

Be it known that I, MAX FREITAG, a subject of the Emperor of Germany, residing at Alfeld-on-the-Leine, Germany, have invented certain new and useful Improvements in or Relating to Machines for Punching and Setting Fasteners in Paper and the like, of which the following is a specification.

This invention relates to machines for reinforcing the edges of paper sheets which have to be punched or perforated and has for its object to provide a machine which will reinforce such sheets in a rapid and efficient manner.

15 Machines are well known in which, during a single revolution of the operating crank the edge of the sheet is reinforced by having glued to it a reinforcing strip of paper which is subsequently punched.

20 According to this invention metal fasteners are simultaneously applied at one or more points in the edge of one or more sheets of paper, the metal fasteners and the paper clenched between them being then perforated by suitable punches forming part of the machine. To this end the machine comprises hollow riveting members or plungers having perforating punches mounted within them, the plungers and punches being 25 each carried by a separate cross head operated by a common actuating shaft.

By employing metal fasteners the edges of the paper are reinforced more efficiently than when a strip of paper is used for the 35 purpose, the unnecessary reinforcement out of the immediate neighborhood of the punched holes is avoided.

In the accompanying drawings which show one form of machine in accordance 40 with this invention,

Figure 1 is a front elevation partly in section.

Fig. 2 is a section on the line A—B of Fig. 1.

45 Fig. 3 is a section on the line C—D of Fig. 1, and

Figs. 4 and 5 show on an enlarged scale the fastening member in side elevation and plan respectively.

50 The machine comprises a crank shaft 2, supported in suitable standards, provided with an operating lever 1 and having two cross-heads or transverse members 3, 4, connected to it by links. The lower cross-head 4 carries hollow reciprocating plungers or riveting members 6 within which are

disposed perforated punches 5 pivotally mounted on the upper cross-head 3. An additional central plunger 7 is also secured to the cross-head 4, the three plungers 6, 7, 60 6 being guided in a portion 8 of the machine frame which lies above the work-supporting table.

Immediately below the plungers 6 in the lower part 9 of the frame hollow dies 10 65 are provided these dies being supported by sleeves 12 which are forced into contact with the dies by means of spiral springs 13 engaging a flange on the sleeves and adjustable nuts 14. A removable dish or cup 15 70 is disposed below the bore of the die, sleeve and nut into which fall the disk of metal and paper punched out of the punches 5.

Leading to the upper end of the hollow die 10 is a feed chute 16 which may be surrounded by a hopper or chamber 17 in which the supply of fasteners is held.

Immediately below the central plunger 7 is a yielding bolt 20 mounted in a perforation 19 in the lower part 9 of the machine 80 frame, the stem 21 of this bolt being surrounded by a spiral spring 23 and having its lower end guided in a nut 22. The spring 23 normally forces the bolt 20 upward so that a stop 24 on its lower end engages the 85 nut 22. A pin 25 secured to the frame 9 extends into a slot 26 formed in the bolt and insures the latter assuming its correct vertical position, and prevents it rotating within its guide. To the upper end of the bolt 20 90 is secured a head 27 comprising a flat central portion 28 and two lateral members 29 which are bent upward as shown in Fig. 3.

The paper 35 is placed upon the supporting table 37 which may be formed of 95 polished wood or other suitable material and is guided into the correct position by its edge engaging a fixed stop 36 or one of three movable stops 31 which are mounted on concentric sleeves 32 and can be rocked by their 100 actuating levers 30 to project through slots 33 in the table 37.

The bent fasteners 18, as shown in Figs. 4 and 5, are of the clench type having projecting spikes 34 on one face adapted to 105 engage corresponding openings in the opposite surface.

The operation of the machine is as follows:—

One or more sheets of paper 35 are placed 110 on the table 37, the edge to be reinforced engaging the stop 29 and the stop 36 (if

the paper is of folio size) or one of the adjustable stops 31 (if it is of smaller size) engaging another edge of the paper and centering it correctly on the table. Fastening members 18 are then fed into the guides and since the latter are perfectly smooth no obstacle is offered to the travel of the fasteners until they reach and straddle the paper 35. The operating lever 1 is then 10 rotated, whereupon the central plunger is depressed and grips the paper between its under-surface and the head 28, the hollow plungers 6 simultaneously descending and clutching the metal fasteners to the edges 15 of the paper. While the plungers 6 are still in contact with the fasteners 18 and are holding them tightly continuous rotation of the shaft 2 causes the punches 5 to descend and perforate the fasteners and the paper between their two surfaces. The 20 portions thus punched out fall through the hollow die 10, sleeve 12 and nut 14 to the dished plate 15 whence they may be periodically removed.

25 Thus in a single complete revolution of the shaft 2 the fasteners are secured to the paper and, together with the latter, are perforated.

30 I claim:

30 1. A machine of the character described, comprising means for feeding a bent fastener into straddling engagement with a paper sheet, means for clutching the fastener to said sheet, and common means for forming a continuous opening that extends completely through the fastener and sheet.

35 2. A machine of the character described, comprising means for feeding a bent fas-

tener into straddling engagement with a 40 paper sheet, means for gripping the sheet, means for clutching the fastener to the sheet and common means for forming a continuous opening that extends completely through the fastener and sheet. 45

3. A machine of the character described, comprising a work table adapted to support a paper sheet, a hollow plunger adapted to clutch a fastener to said sheet, and a punch movable within said plunger and 50 adapted to form a continuous opening that extends completely through the fastener and sheet.

4. A machine of the character described, comprising a work table adapted to support a paper sheet, an adjustable stop for 55 said sheet, a hollow plunger adapted to clutch a fastener to said sheet, and a punch movable within said plunger and adapted to perforate both the fastener and the sheet. 60

5. A machine of the character described, comprising a work table adapted to support a paper sheet, a feed chute adapted to deliver a fastener into straddling engagement 65 with said sheet, a plunger adapted to grip the sheet, a hollow second plunger adapted to clutch the fastener to the sheet, and a punch movable within said hollow plunger and adapted to perforate both the fastener and sheet. 70

In testimony whereof I have hereunto set my hand in presence of two subscribing witnesses.

MAX FREITAG.
